(71) Applicant: **Caterpillar Inc.**, Peoria, IL (US)

(72) Inventors: **Eric Sinn**, Tremont, IL (US); **Douglas Serrurier**, Morton, IL (US); **Rammagy Yoeu**, Dunlap, IL (US)

(73) Assignee: **Caterpillar Inc.**, Peoria, IL (US)

(**) Term: **15 Years**

(21) Appl. No.: **29/762,196**

(22) Filed: **Dec. 15, 2020**

Related U.S. Application Data

(63) Continuation of application No. 29/682,763, filed on Mar. 7, 2019, now Pat. No. Des. 905,765.

(57) **CLAIM**

The ornamental design for an adapter for a ground engaging machine implement, as shown and described.

DESCRIPTION

FIG. 1 is a front perspective view of an adapter for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.

1 Claim, 5 Drawing Sheets
